United States Patent Office

Des. 183,908
Patented Nov. 18, 1958

183,908

INVALID WALKER

Lester L. Bauer, Toledo, Ohio, assignor to Gendron
Wheel Company, Perrysburg, Ohio, a corporation of Ohio

Application December 6, 1956, Serial No. 44,090

Term of patent 3½ years

(Cl. D14—3)

The figure is a perspective view of the invalid walker showing my new design.

The essential feature of my design resides in the portion shown in full lines.

I claim:

The ornamental design for an invalid walker, as shown and described.
